FIG. 1 is a rear perspective view of my new bracket for mounting a video monitor to a bag dispensing rack.

FIG. 2 is a front perspective view thereof.

FIG. 3 is a top plan view thereof.

FIG. 4 is a bottom plan view thereof.

FIG. 5 is a rear elevational view thereof as viewed in FIG. 1.

FIG. 6 is a side elevational view thereof from the left side as viewed in FIG. 1. The opposite side being a mirror image thereof.

FIG. 7 is a front elevational view thereof as viewed in FIG. 1.

FIG. 8 is a front perspective view of the bracket positioned on the front end of a rack.

FIG. 9 is a front perspective view of a monitor positioned on the front of the bracket; and,

FIG. 10 is a rear perspective view of the rack with a monitor positioned on the front of the rack.

The rack and monitor are shown in broken lines for illustrative purposes only and form no part of the claimed invention. The dash line representation of holes in the bracket is also for illustrative purposes only, and is not intended to form a portion of the claimed design.
